UNITED STATES PATENT OFFICE

LOUIS P. TIERS, OF EVANSTON, ILLINOIS, ASSIGNOR TO PROCTOR & SCHWARTZ, INCORPORATED, OF PHILADELPHIA, PENNSYLVANIA, A CORPORATION OF PENNSYLVANIA

SCORING DEVICE FOR SOAP ROLLS

Application filed December 22, 1930. Serial No. 504,135.

This invention relates to scoring devices for use in plastic material treating apparatus. The present invention relates particularly to a scoring device for use with a soap chilling roll, whereby a film of soap, solidifying on the roll, may be scored prior to its removal from the roll, so that the film will be broken up into flakes of substantially uniform size and shape as it is scraped off the face of the roll.

Scoring devices have been employed in the past for marking the film along substantially straight parallel lines running circumferentially of the face of the chilling roll, to divide the film into ribbons of predetermined widths. As these ribbons are subsequently scraped from the face of the roll the soap breaks up into flakes of various unequal sizes.

One object of this invention is to score the soap film by providing parallel undulated or zig-zag scorings in the film on the face of the roll, so that as the film is scraped from the face of the roll it will break up into flakes of substantially uniform size, as determined by the changes in direction of the undulations.

Another object of the invention is to provide a plurality of scoring elements arranged in two separate but parallel series, the respective series being actuated in such a manner that the scorings made by one series will intersect the scorings made by the other series, producing flakes of predetermined uniform shape and size.

The construction and operation of the device will be fully disclosed hereinafter, reference being had to the accompanying drawing, of which;

Figure 1 is an elevation of a soap chilling roll, showing the improved scoring device operating on the face of the roll;

Fig. 2 is a sectional elevation taken on the line 2—2, Fig. 1; and

Fig. 3 is a diagrammatic view showing one form of the intersecting scorings adapted to produce flakes of a predetermined shape.

The chilling roll, shown at 1, is provided with a peripheral film carrying face 2 to which the soap is applied in a more or less

plastic or semi-liquid state. The soap is formed in a relatively thin film on the face 2 and is permitted to solidify thereon, to be subsequently scraped therefrom by a scraper blade or knife 3, the roll 1 being adapted for 55 rotation in the direction indicated by the arrow in Fig. 2.

The roll 1 is provided with a supporting shaft or trunions 4, 4 which are rotatably mounted in suitable bearings, not shown, 60 which are carried by or formed on side frames 5 and 6 respectively.

Any of the well known means may be provided for keeping the roll 1 at a predetermined temperature calculated to cause the 65 soap to chill and solidify on the face 2 of the roll.

The scraping knife 3 is also carried by the frames 5 and 6 and is adapted to be adjustable relative to the face of the roll 2 to obtain the 70 most efficient angle relative to the face 2 for scraping the soap from the roll 1.

The scoring device, forming the subject of the present invention comprises a pair of parallel longitudinally slidable bars 10 and 11 which are slidably mounted in the bearings 12 and 13 carried by the frames 5 and 6 respectively.

The bars 10 and 11 are adapted to be reciprocated longitudinally across the film carrying face 2 of the chilling roll 1.

The bars 10 and 11 respectively carry series of holders 14 and 15, in which are mounted scoring elements 16 and 17 respectively.

The scoring elements in the present instance are in the form of relatively sharp needles or short wires, the points of which are adapted to bear against the chilling surface 2 of the roll 1, so that as the roll is rotated, the scoring elements 16 and 17 will produce grooves or marks in the film of soap carried by the face 2 of the roll 1.

Reciprocation of the bars 10 and 11, and the scoring elements 16 and 17 respectively carried thereby, is effected by a rotary circular cam 20, having a high spot 21 and a low spot 22 diametrically opposed to the high spot 21, the intervening portions of the cam path being in the form of straight faced inclines 23 100

extending between the high and low spots 21 and 22 respectively.

The cam 20 bears against a lug or projection 24 on a head 25 carried on the adjacent ends 5 of the slide bars 10 and 11.

The bars 10 and 11 are further united for simultaneous operation by straps 26 and 27 secured to the slide bars.

The opposite ends of the slide bars 10 and 10 11 are mounted in bores 28 and 29 formed in the bearing 12 and intermediate the end wall of the bore and the end of the slide bar mounted in the bore, is a spring 30, which tends at all times to force the slide bars 10 and 11 to 15 the right as seen in Fig. 1.

Forcing the slide bars 10 and 11 to the right, as above noted, maintains the operating projection 24 of the head 25 in operative engagement with the cam 20 at all times, and 20 as the cam 20 is rotated, this cooperative engagement effects longitudinal reciprocation of the bars 10 and 11 and lateral reciprocation of the scoring elements 16 and 17 carried by the bars 10 and 11 respectively.

25 As shown in Figs. 1 and 3 the lateral movement of the scoring elements 16 and 17 is substantially equal to the spacing of the elements 16 and 17 on the bars 10 and 11.

The scoring elements 17 are preferably 30 aligned respectively with the scoring elements 16 in a direction circumferentially of the roll 1 so that as roll 1 and cam 20 rotate, each aligned pair of scoring elements will move laterally, for example to the right, see 35 the bottom of Fig. 3, producing inclined parallel scorings *a* and *b* respectively. As the cam 20 continues to rotate, and the roll 1 also continues to rotate the scoring elements 16 and 17 will move to the left, producing the 40 inclined parallel scoring lines *a'* and *b'* respectively.

It will be here noted that the left inclines *b'* formed by the scoring elements 17, intersect and cross the right inclines *a*, previously 45 formed by the scoring elements 16.

When making the next right inclines *b* the scoring elements 17 intersect and cross the previously formed left inclines *a'* formed by the scoring elements 16.

50 This intersecting and crossing of the scoring lines made by each circumferentially aligned pair of scoring elements 16 and 17 respectively continues in this manner throughout the operation of the device.

55 The reciprocation of the bars 10 and 11 being substantially equal to the spacing of the scoring elements longitudinally of the bars, causes the turning points of the undulations of the scored lines made by the scoring elements 16 to adjoin with the turning points of the undulations of the scored lines made by the scoring elements 17, 17 at the opposite sides of the line made by the said scoring element 16, the scoring element 17 of the particular pair 16—17, forming lines which at

their turning points adjoin with the turning points of the lines made by the scoring elements 16, 16 of the pairs 16—17 at each of the opposite sides of the particular pair first mentioned.

In this way the entire film F carried on the surface 2 of the roll 1, as it passes the scoring elements 16, 16 and 17, 17, is scored or cross hatched in the manner indicated in Fig. 1, dividing the film into uniform diamond-shaped blocks D, D, which are subsequently removed in this form by the scraping knife 3.

The cam 20 is mounted for rotation on a stud 35 carried by the bearing 13, and is provided, in the present instance with a sprocket 36 wheel around which passes a drive chain 37.

The drive chain 37 also passes around a sprocket wheel 38 secured to a drive shaft 39, rotatably mounted in bearing (not shown) 25 carried by the frames 5 and 6 respectively.

On the drive shaft 39 is a gear 40 which meshes with a gear 41 carried by one of the trunnions of the chilling roll 1 thus, when power is applied to the drive shaft 39, the chilling roll 1 and the cam 20 are rotated at a predetermined speed ratio.

I claim:

1. The combination with a solidifying roll, for plastic materials, of a plurality of scoring elements disposed in spaced relation to each other across the material carrying face of the roll, means for rotating the roll, and means for laterally reciprocating said elements to produce undulated scorings in a 100 layer of material on the said face of the roll.

2. The combination with a solidifying roll, for plastic materials, of a plurality of scoring elements disposed in spaced relation to each other across the material carrying face of the roll, means for rotating the roll, and means for laterally reciprocating said plurality of scoring elements as a unit to produce a series of substantially parallel undulated scorings in a layer of material on the said face of the roll.

3. The combination with a solidifying roll, for plastic materials, of a plurality of scoring elements disposed in spaced relation to each other across the material carrying face of the roll, means for rotating the roll, a second series of scoring elements spaced circumferentially of the roll with respect to the first said series, and means for laterally reciprocating said elements to produce undulated scorings in a layer of material on the said face of the roll.

4. The combination with a solidifying roll, for plastic materials, of a series of scoring elements disposed in relatively spaced relation across the material carrying face of the roll, means for rotating the roll, a second series of scoring elements disposed in relatively spaced relation across the said face of the

roll and in circumferentially spaced relation to the first said series of scoring elements, and means for reciprocating the scoring elements laterally to form undulated intersecting scorings in the layer of material in the said face of the roll.

5. The combination with a solidifying roll, for plastic materials, of a series of scoring elements disposed in relatively spaced relation across the material carrying face of the roll, means for rotating the roll, a second series of scoring elements disposed in relatively spaced relation across the said face of the roll and in substantially circumferential alignment and spaced relation to the respective elements of the first said series of scoring elements and means for reciprocating the scoring elements laterally to form undulated intersecting scorings in the layer of material in the said face of the roll.

6. The combination with a solidifying roll, for plastic materials, of a series of scoring elements disposed in relatively spaced relation across the material carrying face of the roll, means for rotating the roll, a second series of scoring elements disposed in relatively spaced relation across the said face of the roll and in substantially circumferential alignment and spaced relation to the respective elements of the first said series of scoring elements, means for reciprocating the scoring elements laterally to form undulated intersecting scorings in the layer of material on the said face of the roll and means for cooperatively connecting said separate series for simultaneous operation.

7. The combination with a solidifying roll, for plastic materials, of a series of scoring elements disposed in relatively spaced relation across the material carrying face of the roll, means for rotating the roll, a second series of scoring elements disposed in relatively spaced relation across the said face of the roll and in circumferential spaced relation to the first said series of scoring elements, means for operatively connecting said separate series for simultaneous operation, and common actuating means for reciprocating said scoring elements laterally to form undulated scorings in the layer of material on the said face of the roll.

8. The combination with a solidifying roll, for plastic materials, of a series of scoring elements disposed in relatively spaced relation across the material carrying face of the roll, means for rotating the roll, a second series of scoring elements disposed in relatively spaced relation across the said face of the roll and in circumferential spaced relation to the first said series of scoring elements, means for operatively connecting said separate series for simultaneous operation, and a cam for effecting lateral reciprocation of said scoring elements to form undulated

scorings in the layer of material in the said face of the roll.

9. The combination with a solidifying roll, for plastic materials, of a series of scoring elements disposed in relatively spaced relation across the material carrying face of the roll, means for rotating the roll, a second series of scoring elements disposed in relatively spaced relation across the said face of the roll and in circumferential spaced relation to the first said series of scoring elements, means for operatively connecting said separate series for simultaneous operation, a cam for moving said elements laterally in one direction, and resilient means for moving said elements in an opposite direction to form undulated scorings in the layer of material in the said face of the roll.

10. The combination with a solidifying roll, for plastic materials, of a series of scoring elements disposed in spaced relation to each other across the material carrying face of the roll, means for rotating the roll, means for supporting said elements in said predetermined relation and means cooperating with said supporting means for laterally reciprocating said elements to form undulated scorings in a layer of material on the roll.

11. The combination with a solidifying roll for plastic materials, of a bar extending across substantially parallel to the material supporting face of the roll, means for rotating the roll, a series of scoring elements disposed in spaced relation to each other along said bar and means for reciprocating said bar to cause said scoring elements to form undulated scorings in a layer of material on the roll.

12. The combination with a solidifying roll for plastic materials, of a bar extending across substantially parallel to the material supporting face of the roll, means for rotating the roll, a series of scoring elements disposed in spaced relation to each other along said bar, a cam operating against one end of the bar, and resilient means tending to hold said bar end in operative engagement with said cam, to reciprocate said bar and the scoring elements carried thereby, to form undulated scorings in a layer of material on the roll.

13. The combination with a solidifying roll for plastic materials, of a bar extending across substantially parallel to the material supporting face of the roll, means for rotating the roll, a series of scoring elements disposed in spaced relation to each other along said bar, a second bar spaced circumferentially of the roll from the first said bar, a series of scoring elements disposed in predetermined spaced relation on said second bar, means for slidably supporting said bars for longitudinal movement, means for operatively connecting said bars for simultaneous operation, and a cam for effecting recipro-

cations of said bars to produce undulated intersecting scorings on the layer of material on the roll by the respective scoring elements on the slide bars.

14. The combination with a solidifying roll for plastic materials, of a bar extending across substantially parallel to the material supporting face of the roll, means for rotating the roll, a series of scoring elements disposed in spaced relation to each other along said bar, a second bar spaced circumferentially of the roll from the first said bar, a series of scoring elements disposed in predetermined spaced relation on said second bar, means for slidably supporting said bars for longitudinal movement, means for operatively connecting said bars for simultaneous operation, and a cam for effecting reciprocations of said bars to produce undulated intersecting scorings on the layer of material on the roll by the respective scoring elements on the slide bars, and resilient means maintaining the slide bars in operative relation to the common actuating cam.
